APPARATUS FOR FORMING VALVE OR TAPPET HEADS

Application filed November 7, 1929. Serial No. 405,317.

This invention relates to an improved method of, and preferred apparatus for, structurally correlating a relatively soft valve screw head or tappet member and a relatively harder inserted slug or impact receiving piece, and has for its object not only the effecting of manufacturing economies per unit thus assembled, but as well an increased efficiency and permanency of the union between the parts thus effected. The relative degrees of hardness of the two parts thus joined may be made a matter of selection which is determined by the individual conditions of any particular job in hand, and the operative members used in the manner herein described may be varied from quite appreciably, without departure from the fair spirit of this disclosure.

In the drawing:

20 Figure 1 is a sectional elevational view of the cooperating and relatively movable die members employed, with a valve, tappet, or similar article positioned in place therein.

25 Figure 2 is a similar sectional elevational view after the operative action of the die members has taken place upon the valve screw or tappet head.

20 A represents a holding die, through which extends a vertical bore B whose top portion is quite appreciably enlarged, as at C, the upper edges of this enlarged portion being tapered as at D. In this thus recessed die body there is adapted to be placed a valve or tappet body G, whose screwthreaded stem F may depend rather loosely into the lower and smaller bottom portion of the bore B. The diameter of the enlargement C is slightly less, except at its top edges D, than the external or peripheral size of the tappet head G, whose lower edge, when the member is first placed therein, rests non-descendingly about midway between the top and bottom of the enlarged bore portion C as a whole.

45 The top surface of the valve or tappet head G is bored, as at H, for the insertion of a slug J preferably of truncated conical shape, and preferably the top of the tappet or valve body G has been in the first instance so contoured

upwardly projecting rim as K immediately surrounding the bore.

Positioned in axial alignment above the holding die A and its inserted tappet body is a vertically descending die body L, in whose bored under face is inserted, by screw threading or otherwise, a terminally tapered impact member N, whose lower end, which is adapted to engage the top surface of the tappet body, is of the same general curvature as the intended curvature of the tappet body when the process about to be described is completed.

The central portion of this tapered part N is centrally bored, as at P, for the engagement therethrough of the stem Q of the yielding impact member R which may be described as of cross-sectionally T-shape.

This stem Q is designed to descend, as the die body L as a whole descends, upon and in axial alignment with the inserted slug J in

70 the top of the tappet body, and, as brought out in Figure 1, in the initial stages of the operation it extends below the slightly curved under face V of the tappet-engaging part N, so that the lower end of the stem Q encounters the slug J slightly before the under face of the valve-head-engaging body N encounters the top surface of the valve head; it thus serves to hold against displacement the slug J which has previously been positioned within the bore H in the top of the valve or tappet body.

75 Since, however, immediately above the head R of this descending T-shape piece there is positioned a cushion T of rubber or other relatively yielding material, or even a spring in substitution therefor, as the die member L continues this descent, the lower end of the stem Q being already halted from further descent by its contact against the top of the slug J, the rest of the descending die member continues

80 its downward movement, which from that time on is also downward relatively to the slug-engaging stem Q, due to the yielding of the rubber filler T or its equivalent spring.

85 The lower end V of the tappet-engaging member N thus descends crushingly upon the metal of the tappet head immediately surrounding the bore H, and because of the slight space left unoccupied therein by the slightly

90 95 100

tapered slug J, the surrounding metal of the tappet body and particularly the rim K is forced downwardly and spreadingly over the edges of the slug J thus firmly locking it against displacement from the bore H, and making it thereafter structurally integral therewith. This centripetal movement or flowing of the component metal of the tappet head is aided by its compression by the surrounding and unyielding sides of the bore C in the holding die A, so that when the driving stroke of the descending die member is finished, the tappet head is very compact metallurgically with the sides of the bore H in its central part in firm holding engagement about the preferably sloping sides of the insert or slug J. Whatever surplus metal of what was initially the rim K remains projecting to an undesired degree above the plane of the top surface of the head G may thereafter be ground off to the degree desired for neat finish.

This downward impact, to which the valve or tappet body as a whole has thus been subjected, having driven the valve or tappet body as a whole down to the bottom of the space C and its screw-threaded stem portion F having descended accordingly lengthwise of the bore B, the entire finished tappet may be ejected in any desired manner, as by upward drive of the knockout punch member Y.

As soon as the die member L is raised from the contact of its operative parts with the top of the tappet head, the resiliency of the rubber filler T or of the corresponding spring if that be used forces the T-shaped stem piece R and its stem Q downwardly once more relatively to the bore P, so that its projecting lower end is again in position to operatively engage the initially separate slug J which is positioned in the next tappet head blank G that is to be operated upon.

What I claim is:

1. Means for effecting the structural integration of a body of relatively soft metal having a depression in its top surface and an inserted slug of harder metal in the depression comprising a holding die adapted to hold inserted the softer metallic body against centrifugal expansion in the presence of pressure applied to the top surface thereof, and a composite die member having a downwardly projecting portion adapted to first yieldingly engage the top of said slug when the die member as a whole descends, after which the impact and continued pressure of the other portion of the composite die member upon the top surface of the positioned soft metal body acts to force its component metal surrounding its bore centripetally into firm holding engagement against the sides of the hard metal slug.

2. Means for effecting the structural correlation of a metallic body having an open cavity in its top surface, and an inserted slug,

said means comprising a holding die within which such parts so assembled are adapted to be rested, and a descending composite die member adapted to forcibly descend thereupon, such action causing flowage of part 70 of the metallic body to cause seizure of the slug thereby, said descending die having a yieldably downwardly projecting extension adapted to engage the slug before the remainder of the die contacts the metallic body 75 to retain the slug in position during the remainder of the operation.

3. Means for securing a slug in a tappet head having an aperture therein for loosely receiving the slug, comprising a holding die, 80 a composite descending die member adapted to cooperate with the holding die in effecting the centripetal flowage of the metal of the tappet head surrounding said depression about said slug, and a stem carried by said 85 descending die member and projecting downwardly therefrom to engage the slug before the remainder of the die contacts the tappet head, to prevent the slug from undesirably changing its position under the impact of the 90 descending die.

4. The combination, with a holding die wherein there is adapted to be positioned a centrally bored tappet bolt whose head is of slightly greater diameter than that of the 95 bore in said die, of a descending die member positioned in axial alignment therewith and adapted to force the tappet bolt thereinto with a centripetal flowing influence upon the constituent metal of its head, to cause seizure 100 of a slug inserted in its bore, said descending die member being formed of a plurality of relatively movable parts one of which is adapted to impactingly engage the head of said tappet bolt while another engages the 105 top of a slug positioned in the bored top of the tappet bolt before the other part strikes, and means yieldably maintaining said part in engagement with the slug during the remainder of the operation to prevent displacement 110 of the slug.

In testimony whereof I sign this specification.

CLARE L. BRACKETT.
